Primary Examiner — Katrina A Betton

(21) Appl. No.: **29/696,990**

CLAIM

(22) Filed: **Jul. 3, 2019**

The ornamental design for an electronic device mount for vehicles, as shown and described.

(51) LOC (12) Cl. **12-16**

DESCRIPTION

(52) U.S. Cl.

USPC **D12/420**; D12/415

(58) **Field of Classification Search**

USPC D12/420, 415-419, 400, 191, 106, 195,

D12/192, 345, 96, 99

CPC B60R 7/04; B60R 7/08

See application file for complete search history.

FIG. 1 is a perspective view of an electronic device mount for vehicles showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the electronic device mount for vehicles where the electronic device mount for vehicles is in a configuration of use;

FIG. 10 is another perspective view thereof;

FIG. 11 is another perspective view thereof; and,

FIG. 12 is an enlarged view of portion 12 shown in FIG. 1. The broken lines in the drawings depict portions of the electronic device mount for vehicles that form no part of the claimed design.
